2,504,736

TURBINE APPARATUS

Anthony F. Schwendiner, Ridley Park, Manioush Gottlieb, Philadelphia, and Frank A. Meyer, Sharon Hill, Pa., assignors to Westinghouse Electric Corporation, East Pittsburgh, Pa., a corporation of Pennsylvania.

Application September 11, 1945, Serial No. 615,682

9 Claims. (Cl. 137—158)

1

The invention relates to the control of elastic fluid turbines (hereinafter referred to as "steam turbines") used for propulsion purposes and it has for an object to provide apparatus of this character wherein the propulsion speed is varied by speed adjustment of the governing mechanism together with means providing, with a given speed adjustment, for manual operation of the governor valve, independently of the governing mechanism, over the speed range below the speed corresponding to the adjustment, the governing mechanism remaining effective to avoid overspeeding.

A further object of the invention is to provide a turbine having a steam admission valve movable in opening and closing directions in response to speed adjustment of the governor mechanism or in response to movement of a manually-operable member and wherein the latter is operable to limit opening of the valve in response to the governor and the governor is effective to limit opening of the valve when it is under control of the manually-movable member.

Still another object of the invention is to provide the controlling arrangement just described with means operable, in the event of failure of the governor, to disconnect the admission valve from the latter and to move the servo-motor piston to an out-of-the-way position against the force of a spring so that the valve is then under full control of the manually-operable member, the operating piston and the spring remaining effective, should the oil pressure supplied to the operating piston fail for any reason, to move the piston and thereby move the admission valve in a closing direction.

Where an electric drive is used to transmit power from a steam turbine to a ship's propeller, the propulsion speed is usually varied by speed adjustment of the governor. It is desirable, however, under certain conditions, to be able to operate the governor valve manually, independently of the governor and its servo-motor mechanism, for the speed range falling below the speed corresponding to the speed adjustment of the governor. In accordance with the present invention, this result is accomplished by the provision of means which is manually operative to move the governor valve over the range from closed position to the position of opening corresponding to that of the servo-motor piston, such movement being effected freely of the governor and its servo-motor, with the latter remaining effective to respond to overspeed. In the usual arrangement of governor, servo-motor and governor valve, the valve, the servo-motor operating piston and the speed-adjusting member of the governor may be regarded as mechanically connected together, that is, with movement of the speed-adjusting member through its range, both the operating piston and the governor valve move through ranges such that the position of each

2

of the latter is dependent on that of the former. Usually, the operating piston is connected to the valve by means including an operating rod unitary with the piston for transmitting reciprocatory or rectilinear motion from the piston to the valve. If, instead of the operating rod being unitary with the piston, it is formed separately from the latter so as to abut it for movement of the valve in a closing direction and the valve is formed so that steam pressure acting thereon moves it in an opening direction to cause the operating rod to follow the piston, then the arrangement, not only has the capacity for ordinary operation in consequence of moving the speed-adjusting member of the governor, but, with the operating piston in a position corresponding to a given position of the speed-adjusting member of the governor, the operating rod may be moved independently of the piston from the position of the latter to the position for valve closing, and vice versa. Such independent movement is accomplished by an abutment movable manually to engage an abutment fixed in relation to the operating rod, continued movement of the movable abutment being effective to move the valve in a closing direction independently of the piston, and, with manual movement of the movable abutment in the other direction, the bias or unbalancing effect exerted by the steam on the valve is effective to move the valve in an opening direction to cause the operating rod to follow the movable abutment, the rod abutment continuing to engage and move with the movable abutment until the rod abuts the piston, whereupon continued movement of the movable abutment in the same direction results in the latter moving away from the rod abutment. With the movable abutment operatively connected to a manually-operable controlling lever, it not only serves as a means for manual operation of the governor valve under certain conditions, but it also functions to limit the turbine load or steam torque, that is, with a given setting given to the adjustable abutment, the latter limits opening of the valve in response to operation of the governor. Accordingly, a further object of the invention is to provide apparatus having these features of construction and of operation.

A further object of the invention is to provide servo-motor mechanism of the character aforesaid, where the operating rod is capable of being moved independently of the operating piston, with a follow-up connection which may be disconnected from the operating rod and fixed in a position constraining the relay of the servo-motor mechanism to move the servo-motor piston to an out-of-the-way position, thereby making it possible for the adjustable abutment to be moved manually through a range sufficient for operation of the governor valve through its full range.

3

A further object of the invention is to provide a speed control lever operatively connected to the admission valve of a turbine by means of a governor and its servo-motor mechanism, the lever being moveable to effect adjustment of a speed-adjusting member of the governor to effect movement of the valve, together with means including a manually-operable lever, located near to the first lever, for effecting operation of the steam valve independently of the governor and its servo-motor mechanism, independent manual control of the valve being provided for by adjustment of the speed control lever to give the governor a speed setting resulting in positioning of the servo-motor piston such that the lever for manual operation of the valve may be moved to move the latter over the range from its position corresponding to the setting of the servo-motor piston to its closed position.

A further object of the invention is to provide a control arrangement having a pair of levers, as just described, together with means, which is operative to render the servo-motor ineffective to operate the admission valve in response to the governor and to effect movement of the servo-motor piston to an out-of-the-way position so that the lever for manually controlling the admission valve may be moved to move the latter through its full working range, and a spring acting on the piston of the servo-motor and effective at all times, in the event of failure of oil pressure for any reason, to move the piston and thereby move the valve in a closing direction.

These and other objects are effected by the invention as will be apparent from the following description and claims taken in connection with the accompanying drawing, forming a part of this application, in which the figure is a diagrammatic fragmentary view showing the improved governor mechanism for a turbine.

Referring to the drawing more in detail, there is shown a steam turbine 10 having an admission valve, at 11, connected by a lever 12 to the operating rod 14. The admission valve, at 11, has a valve plug 15 connected to a stem or body 16 which provides a piston area subject to the pressure of steam in the chest 17 and directed so that pressure acting thereon tends to open the valve.

The turbine drives a gear pump 20 for delivering oil to the discharge passage 21 constituting a source for supplying oil to means providing oil under pressure varying as a function of the turbine speed and as motive liquid for a servo-motor operative to provide for movement of the valve in opening and closing directions.

The governor means includes centrifugal flyweights 23 connected to the spindle 24 by means of the leaf spring 25 having thrust engagement with the stem 26 of the cup valve 27 slidably mounted in the body 28 carried by the housing 29, the cup valve 27 cooperating with the seat 31 formed at the lower end of the sleeve 32 having a bore 33 and slidably fitting in the cylindrical bore 34 of the body 28. Above the bore 34, the body 28 is formed with a slightly larger bore 35 functioning as a cylinder for the relay piston 36 having an interior chamber or cavity 37 in open communication with the cylinder below the relay and cooperating with the bore 33 to define the governing oil pressure space, generally indicated at 38.

Oil is supplied from the pump discharge passage 21 to the governing oil pressure space, at 38, by means of an orifice 40 extending through

4

the wall of the relay. Pressure of oil in the governing pressure space, at 38, is caused to vary substantially as the square of the speed of the turbine by having the cup valve controlled by the centrifugal flyweights. If there is an increase in speed in consequence of decrease in load, the cup valve 27 is caused to move upwardly in consequence of outward movement of the flyweights to restrict the escape of oil through the annular orifice between the cup valve 27 and the seat 31 to increase the oil pressure in the governing liquid pressure space until the force of liquid pressure acting on the cup valve balances the upwardly-acting centrifugal force.

On the other hand, with decrease in speed, the operation is the reverse, the centrifugal flyweights moving inwardly and the force of liquid pressure acting on the cup valve causing the latter to follow the flyweights in consequence of which the cup valve 27 moves away from the seat 31 slightly to increase the escape of oil from the governing liquid pressure space 38, whereupon decrease in pressure takes place and the valve 15 moves in an opening direction to increase the steam admission until the centrifugal and liquid pressure forces attain a balanced relation.

The relay 36 is positioned by opposed forces of liquid pressure and a spring 41. If the pressure in the governing liquid pressure space, at 38, increases, to maintain a balanced relation of spring and liquid pressure forces, the relay moves upwardly to compress the spring 41 and thereby increases its force. On the other hand, if the pressure in such space declines, the relay moves downwardly to reduce the spring force to maintain the balanced relation of forces.

The relay has a central land 42, which, in the mid or neutral position of the relay, just laps the pressure supply port 43 connected to the pump discharge line 21 and it has upper and lower lands 44 and 45 for covering exhaust ports 46. The housing 29 is formed to provide an operating cylinder 48, and cylinder ports 49 and 50 communicate with the cylinder at opposite sides of the operating piston 51 in the cylinder.

The operating rod 14 extends axially into the operating cylinder 48, and, instead of being unitary with the operating piston 51, it abuts the latter so that movement of the piston in one direction is effective to move the valve 15 in a closing direction and movement thereof in the other direction is independent of the rod, the force of steam pressure acting on the valve being effective to move the latter in an opening direction and to cause the rod to follow the piston.

A spring 52 is arranged in the cylinder below the piston 51 and it biases the latter upwardly to cause it to abut the rod 14 to move the valve in a closing direction against the force of steam pressure acting thereon when the oil pressure above the piston is sufficiently reduced in relation to that below the piston.

A follow-up mechanism is provided for transmitting motion from the operating piston to the relay to restore the latter to neutral position in the event of speed change pursuant to load change, a change in speed resulting in displacement of the relay from neutral position, thereby bringing about movement of the operating piston to move the steam valve in such a direction as to oppose the change in speed, the operating piston moving until the follow-up mechanism operates thereby restores the relay to neutral position.

As shown, the follow-up mechanism includes the lever 53 pivotally connected to the rod 14 at

54 and pivotally connected, at 56, to the rod 57 whose lower end abuts the spring 41. In operation, a change in speed is accompanied by a change in governing oil pressure in the space, at 38, and the force of the latter acting on the relay. In consequence, the relay moves from neutral position and thereby causes the operating piston to be operated, and the operating piston moves until the follow-up mechanism changes the compression of the spring 41 to bring its force into balance with that of the liquid pressure with the relay in neutral or cut-off position.

To effect speed changing adjustment of the governor, the sleeve 32 is raised and lowered by means of a shaft 58 having an eccentric pin 59 operatively connected to the sleeve, the shaft being turned in any suitable manner, as by the bevel gear 60 and the meshing bevel sector 61 mounted on the rock shaft 62 having a crank 63 connected by linkage, at 64, to the controlling lever 65.

Assuming that the pin or crank 59 is at a position 90 degrees from that illustrated, then if the lever 65 is moved in a counterclockwise direction, it will be apparent that the sleeve 32 will be moved downwardly, with the result that less centrifugal force, and, therefore, less speed, will be required for the maintenance of a given governing oil pressure in the space, at 38. On the other hand, if clockwise movement is given to the speed control lever, the contrary operation will take place, the sleeve being moved upwardly with the result that a larger centrifugal force and, therefore, greater speed will be required to maintain the same governing oil pressure in the space, at 38. Hence, by movement of the speed control lever 65 and consequent raising and lowering movement of the sleeve 32, the relationship as between turbine speed and governing oil pressure may be changed, with the result that it is possible, by means of this speed adjustment, to adjust the operating speed of the turbine.

Movement of the steam valve 15 in an opening direction is limited in a variable manner to limit the admission of steam to the turbine and, therefore, the turbine torque. To provide for this operation, movement of the operating piston is transmitted to the steam valve only in the direction for closing the latter, the operating piston being movable independently of the rod 14 in a direction to permit opening of the valve 15 by steam pressure applied thereto, the valve opening and the rod following the operating piston to the extent of movement of the latter. To this end, the rod 14 has an abutment 67 fixed thereto and adapted to engage an abutment 68 positioned by the lever 69 fulcrumed, at 70, and operatively connected by the linkage, at 71, to the lever 72.

As long as the operating rod 14 abuts the operating piston 51 to move with the latter pursuant to response to the relay and the speed-adjusting means, the speed-adjusting lever 65, the operating piston 51, and the steam valve 15 may be regarded, functionally at least, as being connected together, that is, for each position of the lever 65, there is a corresponding position of the operating piston 51 and the admission valve 15. Therefore, where the propeller of a ship is driven from the turbine by means of an electric drive, the speed is variable over a range corresponding to adjustment of the speed control lever 65 of the speed-adjusting mechanism.

Assuming a given setting of the speed-adjusting lever 65 and positions of the operating piston 51 and the steam admission valve 15 corresponding thereto, the operating rod 14 abutting

the piston 51, it will be apparent that the lever 72 may be manually operated to cause the abutment 68 to engage the abutment 67 and move the valve 15 from its position corresponding to adjustment of the speed lever 65 in a closing direction. Thus, the valve 15 is capable of being moved by manual operation of the lever 72 through a range from closed position to the position determined by the speed-adjusted position of the operating piston 51. With the governor and the servo-motor mechanism set, as just pointed out, for a slightly higher speed than for the upper limit for manual control by operation of the lever 72, it will be apparent that the governor mechanism remains effective to move the valve 15 in a closing direction in the event of overspeeding.

In addition to manual operation over a speed range determined by speed adjustment of the governor, as just pointed out, the abutment 68 is positionable by the lever so as to limit the extent of opening of the admission valve in response to operation of the governor and its servo-motor mechanism, that is, if, due to increase in load and consequent decrease in speed, the admission valve is being moved in an opening direction in consequence of downward movement of the operating piston 51, the control rod 14 will follow the operating piston until the abutment 67 fixed thereto engages the abutment 68 to limit the extent of opening of the admission valve, the operating piston 51 being free to continue its downward movement.

If operation of the governor should be impaired for any reason, such as clogging of oil passages or ports, the governor and the servo-motor mechanism may be removed from control of the turbine, the control then being entirely in response to operation of the hand lever 72. In this event, the follow-up lever 53 is disconnected from the control rod 14 by removal of the connecting bolt 73, and the lever is then bolted down to the housing 29 by means of a suitable bolt positioned in the opening 74 formed in the lever and in the aligned tapped opening 75 of the housing. As the lever is pushed down and bolted to the housing, the spring 41 is compressed until the force exerted thereby overcomes the initial force of the spring 76 in the relay cavity, whereupon the spill valve member 77 normally held closed by the spring 76 moves downwardly to place the governing oil pressure space, at 38, in communication with the exhaust by means of the passages or ports 78 and 79 formed in the valve member. The consequent reduction in pressure in the governing oil pressure space, at 38, results in downward movement of the relay to admit motive liquid through the cylinder passage 49 to the upper end of the operating cylinder 48 to move the operating piston downwardly so as not to interfere with full range of operation of the admission valve by movement of the hand lever 72.

With the relay in its lowermost position and supplying oil from the supply passage 21 through the cylinder passage 49 to the upper end of the cylinder to maintain the operating piston in an out-of-the-way position with respect to the control rod 14, as just pointed out, if oil failure should occur for any reason, such as failure of the pump or breakage of an oil line, then it will be apparent that the pressure supplied above the piston 51 is relieved and the spring 52 is thereby rendered effective to move the control rod 14 upwardly to move the steam valve 15 in a closing

direction, this operation taking place irrespective of the position of the hand lever 72 and the movable abutment 68 for the reason that the abutment 67 fixed to the control rod is at all times free to move upwardly relative to the movable abutment.

While the invention has been shown in but one form, it will be obvious to those skilled in the art that it is not so limited, but is susceptible of various changes and modifications without departing from the spirit thereof.

What is claimed is:

1. In means for controlling a turbine, an elastic fluid admission valve for the turbine, means for biasing the admission valve in an opening direction, an operating rod connected to move with the admission valve, a piston movable in one direction to abut the operating rod to move the admission valve in a closing direction against the force of said biasing means and movable in the other direction independently of the operating rod so that the latter follows the piston pursuant to opening movement of the admission valve by said biasing means; means providing liquid under governing pressure varying as a function of speed of the prime mover, means responsive to increase in governing pressure of liquid to cause said piston to move in said one direction to move the valve in a closing direction and responsive to decrease in governing liquid pressure to cause said piston to move in the opposite direction to provide for opening movement of the admission valve by said biasing means, a first abutment fixed with respect to the operating rod, a second abutment cooperating with the first abutment to limit motion of the operating rod in the direction for increase in opening of the admission valve, and means manually operable to adjust the position of the second abutment.

2. Apparatus as claimed in claim 1 with a spring exerting force on the piston for movement of the admission valve in a closing direction against the force of said biasing means.

3. In means for controlling a turbine, an elastic fluid admission valve for the turbine, means for biasing the admission valve in an opening direction comprising a pressure area formed thereon and which is continuously subject to pressure of elastic fluid supplied to the admission valve, an operating rod connected to move with the admission valve, a piston movable in one direction to abut the operating rod to move the admission valve in a closing direction against the force of said biasing means and movable in the other direction independently of the operating rod so that the latter follows the piston pursuant to opening movement of the admission valve by said biasing means, a spring exerting force on the piston in said one direction to abut the operating rod and move the admission valve in a closing direction against the force of said biasing means, means providing liquid under governing pressure varying as a function of speed of the prime mover, means responsive to increase in governing pressure of liquid to supply motive fluid to the spring side of said piston and to exhaust motive fluid from the side of the latter remote from the spring and responsive to decrease in governing liquid pressure to supply motive fluid to said remote side of the piston and to exhaust motive fluid from the spring side thereof, a first abutment fixed with respect to the operating rod, a second abutment cooperating with the first abutment to limit motion of the operating rod in the direction for increase in opening of the admission valve, and means manually operable to adjust the position of the second abutment.

4. In means for controlling a turbine, an elastic fluid admission valve for the turbine, means for biasing the admission valve in an opening direction comprising a pressure area formed thereon and which is continuously subject to pressure of elastic fluid supplied to the admission valve, an operating rod connected to move with the admission valve, means providing liquid under governing pressure varying as a function of speed of the turbine, a servo-motor including an operating cylinder, an operating piston axially aligned with said operating rod, said operating piston being movable in one direction to abut the operating rod to move the valve in a closing direction against the force of said biasing means and being movable in the other direction independently of the operating rod so that said biasing means is effective to move the admission valve in an opening direction to cause the operating rod to follow the operating piston, an operating spring exerting force on the operating piston for movement of the admission valve in a closing direction against the force of said biasing means, a relay movable in response to governing liquid pressure, a spring for exerting force on the relay such that it opposes motion thereof in one direction in response to increase in governing pressure and effects motion thereof in the other direction in response to decrease in governing liquid pressure, said relay being operative to supply motive fluid to the operating cylinder at the operating spring side of the operating piston upon increase in governing liquid pressure and to exhaust motive liquid from the side of the operating piston remote from the operating spring to effect movement of the operating piston in the direction to abut the operating rod and move the valve in a closing direction and being operative to supply motive fluid to the operating cylinder at the side of the operating piston remote from the operating spring and to exhaust

5. In means for controlling a turbine, an elastic fluid admission valve for the turbine, means for biasing the admission valve in an opening direction comprising a pressure area formed thereon and which is continuously subject to pressure of elastic fluid supplied to the admission valve, an operating rod connected to move with the admission valve, a piston movable in one direction to abut the operating rod to move the admission valve in a closing direction against the force of said biasing means and movable in the other direction independently of the operating rod so that the latter follows the operating piston to provide for movement of the valve in an opening direction; a first abutment fixed with respect to the operating rod; a second abutment cooperating with a first abutment to limit motion of the operating rod in the direction for increase in opening of the admission valve; and means manually operable to adjust the position of the second abutment.

6. In means for controlling a turbine, an elastic fluid admission valve for the turbine, means for biasing the admission valve in an opening direction comprising a pressure area formed thereon and which is continuously subject to pressure of elastic fluid supplied to the admission valve, an operating rod connected to move with the admission valve, a piston movable in one direction to abut the operating rod to move the admission valve in a closing direction against the force of said biasing means and movable in the other direction independently of the operating rod so that the latter follows the piston pursuant to opening movement of the admission valve by said biasing

means, a spring exerting force on the piston in a direction to abut the operating rod and move the admission valve in a closing direction, means providing liquid under governing pressure varying as a function of speed of the prime mover, means responsive to increase in governing pressure of liquid to supply motive fluid to the spring side of said piston and to exhaust motive fluid from the side of the latter remote from the spring and responsive to decrease in governing liquid pressure to supply motive fluid to said remote side of the piston and to exhaust motive fluid from the spring side thereof, a first abutment fixed with respect to the operating rod, a second abutment cooperating with the first abutment to limit motion of the operating rod in the direction for increase in opening of the admission valve, means manually operable to adjust the position of the second abutment, manually-controllable means for adjusting the relation as between governing liquid pressure and turbine speed, and means manually operable to reduce said governing pressure so that motive fluid may be supplied continuously to said remote side of the piston to move the latter against said spring to provide for engagement of said abutments so that the second abutment may be moved manually to effect movement of the admission valve to control the turbine.

6. In means for controlling a turbine, an elastic fluid admission valve for the turbine; means for biasing the admission valve in an opening direction comprising a pressure area formed thereon and which is continuously subject to pressure of elastic fluid supplied to the admission valve; an operating rod connected to move with the admission valve; governing means operative to provide liquid under governing pressure varying as a function of the speed of the turbine; a servomotor including an operating cylinder, an operating piston axially aligned with said operating rod, said operating piston being movable in one direction to abut the rod to move the admission valve in a closing direction and being movable in the other direction and independently of the operating rod so that said biasing means is effective to move the admission valve in an opening direction to cause the operating rod to follow the operating piston, an operating spring exerting force on the operating piston for movement of the admission valve in a closing direction against the force of said biasing means, a relay movable in response to governing liquid pressure, and a spring for exerting force on the relay such that it opposes motion thereof in one direction in response to increase in governing liquid pressure and effects motion thereof in the other direction in response to decrease in governing liquid pressure, said relay being operative to supply motive liquid to the operating cylinder at the operating spring side of the operating piston upon increase in governing liquid pressure and to exhaust motive liquid from the side of the operating piston remote from the operating spring to effect movement of the operating piston in the direction to abut the operating rod and move the admission valve in a closing direction and being operative to supply motive liquid to the cylinder at the side of the operating piston remote from the operating spring and to exhaust motive liquid from the operating spring side thereof to effect movement of the operating piston in the other direction independently of the operating rod so that the latter may follow the operating piston to provide for movement of the admission valve in an opening direction by said biasing means.

direction by said biasing means; a follow-up lever operatively connected to the operating rod and abutting the relay spring so that the force of the latter is changed pursuant to operating piston movement to restore the relay to the neutral or cut-off position with the forces acting thereon in equilibrium; a first abutment fixed with respect to the operating rod; a second abutment cooperating with the first abutment to limit motion of the operating rod in the direction for increase in opening of the admission valve; and means manually operable to adjust the position of the second abutment.

7. In means for controlling a turbine, an elastic fluid admission valve for the turbine; means for biasing the admission valve in an opening direction comprising a pressure area formed thereon and which is continuously subject to pressure of elastic fluid supplied to the admission valve; an operating rod connected to move with the admission valve; governing means operative to provide liquid under governing pressure varying as a function of the speed of the turbine; a servomotor including an operating cylinder, an operating piston axially aligned with said operating rod, said operating piston being movable in one direction to abut the rod to move the admission valve in a closing direction against the force of said biasing means and being movable in the other direction and independently of the operating rod so that said biasing means is effective to move the admission valve in an opening direction to cause the operating rod to follow the operating piston, an operating spring exerting force on the operating piston for movement of the admission valve in a closing direction against the force of said biasing means, a relay movable in response to governing liquid pressure, and a spring for exerting force on the relay such that it opposes motion thereof in one direction in response to increase in governing liquid pressure and effects motion thereof in the other direction in response to decrease in governing liquid pressure, said relay being operative to supply motive liquid to the operating cylinder at the operating spring side of the operating piston upon increase in governing liquid pressure and to exhaust motive liquid from the side of the operating piston remote from the operating spring to effect movement of the operating piston in the direction to abut the operating rod and move the admission valve in a closing direction and being operative to supply motive liquid to the cylinder at the side of the operating piston remote from the operating spring and to exhaust motive liquid from the operating spring side thereof to effect movement of the operating piston in the other direction independently of the operating rod so that the latter may follow the operating piston to provide for movement of the admission valve in an opening direction by said biasing means; a follow-up lever operatively connected to the operating rod and abutting the relay spring so that the force of the latter is changed pursuant to operating piston movement to restore the relay to the neutral or cut-off position with the forces acting thereon in equilibrium; a first abutment fixed with respect to the operating rod; a second abutment cooperating with the first abutment to limit motion of the operating rod in the direction for increase in opening of the admission valve; means manually operable to adjust the position of the second abutment; and manually-controllable means for adjusting the relation as between governing liquid pressure and turbine speed.

8. In means for controlling a turbine, an elastic fluid admission valve for the turbine; means for biasing the admission valve in an opening direction comprising a pressure area formed thereon and which is continuously subject to pressure of elastic fluid supplied to the admission valve; an operating rod connected to move with the admission valve; governing means operative to provide liquid under governing pressure varying as a function of the speed of the turbine; a servo-motor including an operating cylinder, an operating piston axially aligned with said operating rod, said operating piston being movable in a first direction to abut the rod to move the admission valve in a closing direction and being movable in the other direction and independently of the operating rod so that said biasing means is effective to move the admission valve in an opening direction to cause the operating rod to follow the operating piston, an operating spring exerting force on the operating piston for movement of the admission valve in a closing direction against the force of said biasing means, a relay movable in response to governing liquid pressure, and a spring for exerting force on the relay such that it opposes motion thereof in one direction in response to increase in governing liquid pressure and effects motion thereof in the other direction in response to decrease in governing liquid pressure, said relay being operative to supply motive liquid to the operating cylinder at the operating spring side of the operating piston upon increase in governing liquid pressure and to exhaust motive liquid from the side of the operating piston remote from the side of the operating piston to effect movement of the operating piston in the direction to abut the operating rod and move the admission valve in a closing direction and being operative to supply motive liquid to the cylinder at the side of the operating piston remote from the operating spring and to exhaust motive liquid from the operating spring side thereof to effect movement of the operating piston in the other direction independently of the operating rod so that the latter may follow the operating piston to provide for movement of the admission valve in an opening direction by said biasing means, a follow-up lever operatively connected to the operating rod and abutting the relay spring so that the force of the latter is changed pursuant to operating piston movement to restore the relay to the neutral or cut-off position with the forces acting thereon in equilibrium; a first abutment fixed with respect to the operating rod; a second abutment cooperating with the first abutment to limit motion of the operating rod in the direction for increase in opening of the admission valve; means manually operable to adjust the position of the second abutment; and means manually operable to reduce said governing pressure so that motive fluid may be supplied continuously to said remote side of the operating piston to move the latter against said operating spring to provide for engagement of said abutments so that the second abutment may be moved manually to effect movement of the admission valve to control the turbine.

9. In means for controlling an elastic fluid turbine, an elastic fluid admission valve for the turbine; means for biasing the admission valve in an opening direction comprising a pressure area formed thereon and which is continuously subject to pressure of elastic fluid supplied to the admission valve; an operating rod connected to move with the admission valve; governing means

operative to provide liquid under governing pressure varying as a function of the speed of the turbine; a servo-motor including an operating cylinder, an operating piston axially aligned with said operating rod, said operating piston being movable in a first direction to abut the rod to move the admission valve in a closing direction and being movable in the other direction and independently of the operating rod so that said biasing means is effective to move the admission valve in an opening direction to cause the operating rod to follow the operating piston, an operating spring exerting force on the operating piston for movement of the admission valve in a closing direction against the force of said biasing means, a relay movable in response to governing liquid pressure, and a spring for exerting force on the relay such that it opposes motion thereof in one direction in response to increase in governing liquid pressure and effects motion thereof in the other direction in response to decrease in governing liquid pressure, said relay being operative to supply motive liquid to the operating cylinder at the operating spring side of the operating piston upon increase in governing liquid pressure and to exhaust motive liquid from the side of the operating piston remote from the operating spring to effect movement of the operating piston in the direction to abut the operating rod and move the admission valve in a closing direction and being operative to supply motive liquid to the cylinder at the side of the operating piston remote from the operating spring and to exhaust motive liquid from the operating spring side thereof to effect movement of the operating piston in the other direction independently of the operating rod so that the latter may follow the operating piston to provide for movement of the admission valve in an opening direction by said biasing means, a follow-up lever operatively connected to the operating rod and abutting the relay spring so that the force of the latter is changed pursuant to operating piston movement to restore the relay to the neutral or cut-off position with the forces acting thereon in equilibrium; a first abutment fixed with respect to the operating rod; a second abutment cooperating with the first abutment to limit motion of the operating rod in the direction for increase in opening of the admission valve; means manually operable to adjust the position of the second abutment; manually-controllable means for adjusting the relation as between governing pressure and turbine speed; and means manually operable to reduce said governing pressure so that motive fluid may be supplied continuously to said remote side of the operating piston to move the latter against said operating spring to provide for engagement of said abutments so that the second abutment may be moved manually to effect movement of the admission valve to control the turbine.
